CONDITION RESPONSIVE FUZING SYSTEM

Thomas C. Smith, Poughkeepsie, N.Y., assignor, by mesne assignments, to the United States of America as represented by the Secretary of the Navy

Filed May 27, 1952, Ser. No. 290,285

4 Claims. (Cl. 102—70.2)

This invention relates to a fusing system for explosive missiles, and in particular, to a fusing system for missiles which are automatically armed some predetermined time after they are launched and the act of arming prepares the fusing system to be responsive to a plurality of conditions, any one of which may cause actual detonation of the missile.

It has been found that the most vulnerable part of a ship, based upon damage which might be inflicted by a severe detonation outside of its hull, is the region of the chine.

Accordingly, it is an object of the present invention to provide a fusing system whereby the missile is caused to detonate under water without actual contact with the ship's hull.

It is another object to provide means to establish a sufficient time delay previous to the detonation to permit the missile to traverse its prescribed trajectory from its water entry position to a point approximately underneath the ship's keel.

It is still another object of the fusing system to provide means causing the detonation of the missile, should it, during the course of its trajectory, impact a solid object either while in the air or under water.

It is an additional object to provide means coacting with the last mentioned means whereby the actual detonation of the missile is momentarily delayed after impact, thus permitting the missile to pass through a wall of the solid object before the detonation occurs.

It is a further object to provide an automatic self-contained circuit testing means operable after the missile has been launched whereby, if any defect be present in the electrical circuits of the fusing system, a premature detonation of the missile is prevented.

It is a still further object to provide means whereby a premature detonation of the missile is prevented mechanically both prior to launching and for a predetermined time after launching.

Other objects will be obvious from a detailed study of the specification in the light of the accompanying drawing, in which Figure 1 is a schematic diagram of the system and the following detailed description refers to indicia and reference numerals which appear on the drawing, and Figure 2 is a schematic diagram of an alternative arrangement of the left half of Figure 1.

Referring first to Figure 1, the actual detonation of the missile is controlled by any one of three explosive trains 10, 11, and 12. The continuity between these trains and their respective initiating means is mechanically interrupted by two plungers 13 and 14 arranged transversely of the trains. Plunger 13 is hydraulically operated by means of hydrodynamic pressure entering through a passage 13a upon the entry of the missile into water and acting against a distortable diaphragm 15, and plunger 14 is operated through the means of a pyrotechnic device 14a, more commonly referred to as an arming squib whose gas pressure, upon initiation, acts against a distortable diaphragm 16. Switches 17 and 18,

each having a plurality of contacts 17 and 18, a, b, and c respectively, are operated in conjunction with the plungers 13 and 14 respectively, and provide a means for making and/or breaking various electrical circuits to be described in detail hereinafter.

Included also in the system are two cold cathode diode tubes 19 and 20; four condensers, 21, 22, 23 and 24; an explosively operated single pole, single throw switch 25; and three primers, 26, 27 and 28 for initiating the firing of the detonators 13c, 13b, and 14c of the explosive trains 10, 11, and 12 respectively.

From a general inspection of the connections to and from switch 17, it will be seen that the function of this switch is to connect either primer 26, or primers 27 and 28 to an activating source, the arrangement of the contacts of the switch being determined by the position plunger 13 has been caused to assume by conditions external to the missile. Until the missile enters water primer 26 is connected through a normally closed contact of the switch 17 to one side of a source of electrical energy, condenser 22, and upon entry into water thus activating plunger 13 as before mentioned, the normally closed contact is opened and two other contacts are closed, the first of which supplies electrical energy from one side of the same source to one side of primer 27 and the other of the newly closed contacts initiates the timing circuit 20, 24, and 43 for the primer 28. The necessity for opening the normally closed contact mentioned above arises from the fact that it is entirely possible for primer 26 to act as a low resistance shunt across primer 27 after the missile has entered water thus dissipating the energy from condenser 22 to the extent that it is insufficient to initiate primer 27.

Switch 18 has a two-fold purpose and provides a means, first, to break the original parallel connections between condensers 21, 22 and 23, and, second, to isolate each of the same from each other and the pair of external conductors 29 and 30 through which their initial electrical energy was received. Through this latter isolation feature, a premature or accidental discharge of the condensers is prevented. Switch 18 is activated through means to be explained hereinafter when condenser 23 is charged to a voltage sufficient to cause cold cathode diode tube 19 to become conductive.

In the embodiment of the invention herein disclosed, condenser 21 energizes a timing circuit at the time of water entry including condenser 24 and cold cathode diode tube 20 which ultimately fires primer 28 after the missile is under water and does not experience an impact, or it energizes the primer 27 after an impact by the missile with an object under water. Condenser 22, on the other hand, energizes the remainder of the circuits' testing means and/or fires primer 26 to detonate the missile after an impact in air.

Thus, it will be seen that, by the provision of two condensers, 21 and 22, each serving as an independent source of electrical energy, and two switches, 17 and 18, each responsive to conditions external to the missile, any energy required for the initiation of primers, prior to the initiation of the timing circuit from condenser 21 and including 20, 24, and 43, is taken only from condenser 22, thus permitting the maintenance of a uniform voltage on condenser 21 which condition is a prime factor in controlling the accuracy of the timing circuit. Under these circumstances it may be said that the timing and detonation circuits within the missile are relatively independent of each other.

The fusing system represented schematically in Figure 1 is activated by means of electrical energy received for a determinable time duration via a pair of conductors 29 and 30 leading from the fuze to an external source of D.C. potential (not shown). It is also preferred for

safety reasons that the charge is not imparted to the system until after the actual launching of the missile. Means for effecting the energization and timing the duration of the energization of an electrical circuit or circuits are well known and form no part of this invention, *per se*, and are not described here.

The voltage applied to conductors 29 and 30 charges the condensers 21, 22, and 23 connected in parallel. The circuit arrangement to accomplish the charging of these condensers is wire 29 to one side of condenser 21; wire 31, contact *a* of switch 18, wire 32 to one side of condenser 22; and through resistor 35 to one side of condenser 23. The other side of the circuit to these condensers is wire 30, contact *b* of switch 18, wire 33 to condensers 21 and 22; and contact *c* of switch 18, wire 34 to condenser 23. The high resistance 35 leading to condenser 23 prevents that condenser from charging at the same rate as condensers 21 and 22. The latter condensers are charged to within predetermined voltage limits by the initial potential received via the connecting conductors 29 and 30 while condenser 23, due to the high resistance 35, is charged to a lesser degree and, in any event, to a voltage less than that required to effect breakdown of cold cathode diode 19. Part of the charge in condensers 21 and 22 is transferred to condenser 23 through a circuit from one side of condenser 21 via wire 31, contact *a* of switch 18 and wire 32, and one side of condenser 22 via wire 32, resistance 35 to one side of condenser 23. The circuit is completed from the other side of condensers 21 and 22 via wire 33, contacts *b* and *c* of switch 18, and wire 34 to the other side of condenser 23.

Connected in parallel with condenser 23, are the explosive switch 25 and the arming squibb 14a, the latter containing a pyrotechnic delay of short duration. A cold cathode diode tube 19 is arranged in one side of the parallel circuit. Thus, when the condenser 23 has been charged to a sufficient voltage from the combination of potential sources previously described, the tube 19 will become conductive sufficient to actuate explosive switch 25, the contacts of which quickly close, and the pyrotechnic delay 14a is initiated. Shortly thereafter diaphragm 16 deforms due to the accumulated gas pressure, thereby opening contacts 18a, b, and c of switch 18, and moving plunger 14 so that the detonator 14c and the portion 14b of the explosive train 10 contained within the plunger 14 are in line with the explosive trains 12 and 10 respectively.

Attention is called at this point to the immediate closing of switch 25, and the delayed opening of switch 18 and movement of plunger 14. From a study of the circuit arrangement in the drawing to the left of switch 25, it will be obvious that, upon the closing of switch 25 and the resultant energization of wire 38, a short circuit, improperly wired switch, or other defect in the apparatus schematically represented in that part of drawing, may result in a premature firing of one or more of the primers 26, 27, and 28. However, since each of the explosive trains 10, 11, and 12 are effectively blocked by a portion of either of the plungers 13 or 14, a premature detonation of the missile is prevented. For example, it may be assumed that the impact jiggle switch 36 is defective or has been caused to assume a closed position for some unknown reason, then the immediate closing of switch 25 would complete a circuit from one side of condenser 22 through wire 37, closed switch 25, and wire 38 to one side of the primer 26, and from the other side of condenser 22 through wires 32 and 39, contact *a* of switch 17, and wire 40 to the other side of primer 26 resulting in the firing of that primer. The missile will not detonate, however, due to the explosive train 10 being blocked by the as yet unmoved plunger 14 due to the delayed action of the pyrotechnic device 14*a* for operating that plunger.

In another example, it may be assumed that in addition to switch 36 being defective, wires 39 and 41 were inter-

changed at their connection with switch 17 during assembly. Under such an assumed condition, the circuit to the one side of primer 26 would be completed from one side of condenser 22 via wire 37, closed switch 25, and wire 38 as before; and to the other side thereof via wire 32, contact *a* of switch 18 and wires 41 and 40. Here, again, the firing of primer 26 will not cause the detonation of the missile since plunger 14 is delayed in its movement to complete the explosive train.

10 Continuing now the description of the normal operation of the fusing system, an explanation of the three separate explosive trains, the firing of any one of which will suffice to detonate the missile, will be made. Explosive train 10 functions upon impact by the missile with a solid object in air, train 11 functions upon an impact with an object under water, and train 12 functions without an impact under water after the passage of a definite time period from the moment of water entry.

The first condition, that is a detonation of the missile following an impact in air, results from a firing of explosive train 10. This is accomplished by the activation of primer 26. From the prior description it will be seen that switch 25 has been closed and, after a short delay, plunger 14 has moved so that the section 14b of explosive train 10 contained within the plunger is in line with the remainder of the train 10.

The circuit for the electrical firing of primer 26 is completed, upon the closing of impact switch 36 by the impact of the missile with a solid object in air, from one side of 30 condenser 22, wire 37, closed switch 25, wire 38, primer 26, wire 46, contact *a* of switch 17, wires 39 and 32 to the other side of the condenser 22. The primer 26 contains a short pyrotechnic delay means whereby the actual firing of the detonator 13c and its associated explosive train 10, 35 and the resultant detonation of the missile, is held back sufficiently to enable the missile to penetrate the wall of the contacted object before the detonation occurs.

The second condition, that is, a detonation of the missile following an impact with a solid object under water, results from a firing of explosive train 11. This is accomplished by the firing of primer 27. As before, the prior description covers the closing of switch 25 and the movement of plunger 14. However, subsequent to launching and at the instant of entry of the missile into water, plunger 13 and its associated switch 17 are moved by means of the external hydrodynamic pressure, effective via passage 13a and acting upon distortable diaphragm 15. This device is only schematically presented here and is not described in detail since it forms no part of the present invention per se. The movement of the

50 of the present invention, per se. The movement of the plunger 13 places the detonator 13b of explosive train 11 in line with the remainder of that train. The instantaneous movement of switch 17 associated with the plunger 13 opens contact *a* and closes contact *b* of switch 17. The 55 shock of the impact of the missile with water may or may not activate impact switch 36, depending upon its sensitivity and the velocity, weight, shape, and angle of water impact of the missile. If switch 36 is closed, the

60 impact of the missile. If it does, primer 26 will be fired through the circuit previously traced after an impact in air. The explosive train 10 will not be fired, however, since the pyrotechnic delay in primer 26 will be sufficient to enable the relatively instantaneous movement of the plunger 13 to move detonator 13c within the plunger out of line with respect to the remainder of the train 10 before the firing of primer 26 is completed. The detonation

65 fore the firing of primer 26 is completed. The detonation of the missile is accomplished by a subsequent closing of the impact switch 36 resulting from an impact of the missile with a solid object under the water. The electrical circuit is from one side of condenser 21, wire 37, closed switch 25, wire 38, closed impact switch 36, primer 27, wire 42, contact 17b of switch 17, and wires 41 and 31 to the other side of condenser 21. The primer 27 contains a short pyrotechnic delay means whereby the actual firing of the detonator 13b and its associated explosive train 11, 70 and the resultant detonation of the missile is held back.

75

sufficiently to enable the missile to penetrate the wall of the contacted object before detonation occurs.

The third condition, that is, a detonation of the missile under water without impact with a solid object, results from a firing of explosive train 12. This is accomplished by the firing of primer 28. The previous description has covered the closing of switch 25, and the movement of plunger 14 subsequent to launching but before entry of the missile into water. Plunger 13, upon entry of the missile into water, is moved as previously described. The movement of these plungers also results in the movement of the contacts of their associated switches.

The movement of plunger 13 closes contact 17c of switch 17 which, in turn, completes a circuit whereby condenser 24 is charged from condenser 21 through the following circuit; one side of condenser 21, wire 31, wire 41, contact c of switch 17, and resistor 43 to one side of condenser 24, and from the other side thereof, through wire 38, closed switch 25, and wire 37 to the other side of condenser 21. The high resistance 43 interposed in the circuit delays the buildup of voltage in condenser 24. When this condenser has been charged to a sufficient voltage, a cold cathode diode tube 20, arranged in series with primer 28 and across condenser 24, will become conductive sufficient to actuate and fire the primer 28. Since plunger 14 has previously been moved to a position whereby the detonator 14c, contained within the plunger is in line with a remainder of the explosive train 12, the detonator 14c and its associated explosive train 12 will be fired and the missile detonated. It will be obvious that under the last described arrangement the detonation of the missile has been accomplished after a definite time delay subsequent to its entry into water and without impact with an object.

While the arrangement according to Figure 1 is entirely practical, it will be obvious that the sensitivity of impact switch 36 must be adjusted within certain definite limits which may not be wide enough for a specific use of the missile. Although it may be sensitive enough to operate upon an impact of the missile with water when entering the same it must not remain closed during water travel of the missile and on the other hand, the sensitivity must be sufficient to permit closure of the switch upon an impact of the missile with a solid object under water. If the switch is too sensitive, forces incidental to the deceleration of the missile while passing through water may be sufficient to hold the switch closed and, thus, prematurely detonate the missile. If the switch is not sufficiently sensitive, the missile will fail to detonate upon impact with a light target while in the air.

In order to avoid these practical difficulties in adjusting the sensitivity of switch 36, the arrangement according to Figure 2 wherein two impact switches, 36 and 36' are provided, may be utilized. In this arrangement, switch 36 is relatively more sensitive than switch 36', the latter being operable only when the missile impacts an object under water while the former may be operated solely by the missile penetrating relatively light material above the water. Since each switch is connected to a separate primer, the energizing circuit for which includes a different condenser, the continued closure of the more sensitive switch 36 will not deenergize the source of potential for the other switch 36', and (see Fig. 1) a premature explosion of primer 27 while the missile is travelling under water is prevented.

Referring now to Figure 2, the testing circuit from one side of condenser 22 through wire 38 to relatively more sensitive impact switch 36, wire 38', primer 26, wire 40, contact 17a of switch 17 and wire 39 to the other side of condenser 22 will function as before. Likewise the same circuit will cause the detonation of the missile after contact with a solid object in air.

Under the second condition where the missile is detonated following an impact with a solid object under water, switch 36 is closed when the missile contacts the water,

but as has been before explained, plunger 13 is moved by external hydrodynamic pressure and detonator 13c moved out of line with the remainder of the explosive train 10 and, at the same time, switch 17 is moved to open contact 5 a and close contacts b and c. Thus, even if primer 26 were to be fired by the circuit traced above, the missile would not be detonated, and, if switch 36 were held closed by the deceleration of the missile in the water, energy from condenser 22 only would be discharged.

10 When switch 17 is moved by plunger 13, condenser 21 is connected to the timing circuit governed by cold cathode diode tube 20 as before, and primer 27 is connected through wire 38" and relatively less sensitive impact switch 36' to a circuit including this same condenser 21.

15 Thus, it will be seen that the provision of two energy sources (condensers 21 and 22) for the various circuits within the missile fuzing system and two impact switches (36 and 36') operated according to deceleration producing conditions prevailing outside the missile, activation 20 of one of the firing trains 10-12 inclusive in a predetermined manner according to the prevailing conditions is accomplished.

25 Various modifications are contemplated and may obviously be resorted to without departing from the spirit and scope of the invention, as only preferred embodiments thereof have been disclosed.

What is claimed is:

30 1. In a fuze for detonating the explosive charge of a missile, a first means for detonating the charge comprising a primer, a detonator, and an explosive train, a plunger carrying said detonator, a circuit comprising an impact switch and said primer whereby the primer may be detonated by actuation of said impact switch, means for moving said plunger into said position in which said detonator 35 is out of alignment with said train, a second means for detonating said explosive charge, comprising a second train and a primer, a second detonator carried by said plunger and moved into alignment with said second primer and said second train by said plunger, means to ignite said second primer, and a third means for detonating the charge a predetermined time after movement of said second plunger.

35 2. In a fuze for detonating the explosive charge of a missile, a first means for detonating the charge comprising a primer, a detonator, and an explosive train, a first 40 plunger carrying a portion of said train, a second plunger carrying said detonator, an arming squib having a time delay for moving said first plunger to said position in which said portion of said train is in alignment with said train, a circuit including said arming squib and means

45 50 for energizing said circuit to ignite said squib, a second circuit comprising an impact switch and said primer whereby the primer may be detonated by actuation of said impact switch, means for moving said second plunger into said position in which said detonator is out of alignment with said train, a second means for detonating said explosive charge, comprising a second train and a primer, a second detonator carried by said second plunger and moved into alignment with said second primer and said second train by said plunger, means to ignite said second primer, and a third means for detonating the charge, 55 comprising a third primer, a third train and a third detonator, said third detonator being moveable by said first plunger into a position in alignment with said train, a third circuit including the third primer and means for energizing said third primer a predetermined time after movement of said second plunger.

60 60 65 3. In a fuze for detonating the explosive charge of a missile, a first means for detonating the charge comprising a primer, a detonator, and an explosive train, a first plunger carrying a portion of said train, a second plunger carrying said detonator, an arming squib having a time delay for moving said first plunger to a position in which said portion of said train is in alignment with said train, 70 75 a circuit including said arming squib and means for ener-

gizing said circuit to ignite said squib, a testing switch, explosive means for closing said testing switch in parallel with said arming squib, whereby said energizing circuit will first ignite said explosive means and close said testing switch and thereafter detonate said arming squib, a second circuit comprising an impact switch said testing switch and said primer whereby the primer may be detonated by actuation of said impact switch, means communicating with the exterior of said missile and adapted to be actuated by hydrodynamic pressure for moving said second plunger into a position in which said detonator is out of alignment with said train, a second means for detonating said explosive charge, comprising a second train, a primer, and a second detonator carried by said second plunger and moved into alignment with said second primer and said second train by said plunger, switch means actuated by said second plunger to connect said impact switch to said second primer, and a third means for detonating the charge, comprising a third primer, a third train and a third detonator, said third detonator being moveable by said first plunger into a position in alignment with said train, a third circuit including the third primer and means for energizing said third primer a predetermined time after movement of said second plunger.

4. In a fuze for detonating the explosive charge of a missile, a first means for detonating the charge comprising a primer, a detonator, and an explosive train, a first plunger carrying a portion of said train, a second plunger carrying said detonator, an arming squib having a time delay for moving said first plunger to a position in which said portion of said train is in alignment with said train,

a circuit including said arming squib and means for energizing said circuit to ignite said squib, a testing switch, explosive means for closing said testing switch in parallel with said arming squib, whereby said energizing circuit will first ignite said explosive switch and close same and thereafter detonate said arming squib, a second circuit comprising an impact switch, said explosive switch and said primer whereby the primer may be detonated by actuation of said impact switch, means communicating at one side with the exterior of said missile and adapted to be actuated by hydrodynamic pressure for moving said second plunger into a position in which said detonator is out of alignment with said train, a second means for detonating said explosive charge, comprising a second train and a primer, a second detonator carried by said second plunger and moved into alignment with said second primer and said second train by said plunger, a second impact switch, switch means actuated by said second plunger to connect said second impact switch to said second primer, and a third means for detonating the charge, comprising a third primer, a third train and a third detonator, said third detonator being moveable by said first plunger into a position in alignment with said train, a third circuit including the third primer and means for energizing said third primer a predetermined time after movement of said second plunger.
